UNITED STATES PATENT OFFICE.

GOTTFRID OLSON, OF MINNEAPOLIS, MINNESOTA, ASSIGNOR, BY MESNE ASSIGNMENTS, TO STEINER SALES COMPANY, OF SALT LAKE CITY, UTAH, A CORPORATION OF UTAH.

TOWEL CABINET.

Application filed October 14, 1921. Serial No. 507,598.

To all whom it may concern:

Be it known that I, GOTTFRID OLSON, a citizen of the United States, resident of Minneapolis, county of Hennepin, State of Minnesota, have invented certain new and useful Improvements in Towel Cabinets, of which the following is a specification.

The object of my invention is to provide a cabinet of simple, inexpensive construction wherein a roll or bolt of clean toweling may be placed, with the clean web in convenient position to be grasped by the user, with means for automatically checking the delivery of the clean web when a predetermined length has been drawn out.

The invention consists generally in various constructions and combinations, all as hereinafter described and particularly pointed out in the claims.

20 In the accompanying drawings forming part of this specification,

Figure 1 is a vertical sectional view through a cabinet embodying my invention,

25 Figure 2 is a sectional view on the line 2—2 of Figure 1,

Figure 3 is a detail sectional view, showing a modified construction,

30 Figure 4 is a perspective view of the roll and locking dog,

Figure 5 is a detail sectional view, showing the clean towel roll above the feed roll,

Figure 6 is a similar view of a metal cabinet, with the roll mounted in a tilting container.

35 In the drawing, 2 represents the side walls of the cabinet, having in the lower portion a soiled towel receptacle 3 and a box 4 in the upper portion of the cabinet provided with a rear hinged door 5 and adapted to contain a roll of clean toweling 6. A gap 7 is provided between the upper edge of the door and the top of the box, through which the web of clean toweling may be drawn, the hinge of the door being preferably spring 40 to hold it in its closed position with a yielding pressure.

45 In the top of the cabinet is a feed roll 8 over which the web of clean toweling passes and down through a space 9 between the box 4 and a front panel 10 which closes the upper portion of the cabinet. Beneath this panel an opening is provided through which the user of the towel may reach the depend-

ing web and pull it to the front of the cabinet. The roll 8 has a cam 11 on one end, 55 provided with a shoulder 12 and a roll 13 is mounted in the wall of the cabinet near the feed roll 8 and is provided with a dog 14 to ride on the periphery of the cam 11 during the feed of the towel and drop by 60 gravity out of contact with said cam when the pull on the towel is released, the friction of the web of toweling on the surface of the roll 13 being sufficient to lift the dog from its depressed inactive position to a point where 65 it will contact with the stop 12 and positively check revolution of the feed roll and further feed of the towel. Slippage of the web of towel on the feed roll is prevented by a peripheral surface 15 of rubber, sand 70 paper, or other suitable material.

In Figure 3 I have shown slots 16 in the side wall of the cabinet, and a bar 17 that is mounted to slide vertically in said slots and is provided with a lower surface 18 for 75 contact with the web of toweling, the pull of the web thereon operating to raise the bar vertically in said slots and position the dog 19 to engage the stop on the cam and check movement of the feed roll.

80 In Figure 5 I have shown another modification which consists in arranging the box 20 for the clean towel roll in the top of the cabinet and providing a door 21 in the front through which access may be had to the 85 box. A floor 22 supports the roll and a gap 23 provided between this floor and the rear wall of the box allows the towel to be fed therethrough to the rolls beneath. The stop device corresponds to the one 90 shown in Figure 1, except that a pin 24 is mounted in the wall of the cabinet to engage the dog and limit its downward movement when the pull of the towel is released. The clean towel passes down under the roll 13 and over the feed roll 8 in the manner shown with reference to Figure 1.

95 In Figure 6 another modification is shown, which consists in providing a metal casing 25 having a container 26 in the top thereof, hinged at its lower forward portion 27 and adapted to swing outwardly on this hinge and allow the insertion of the roll of toweling. A rear wall 28 is provided over 100 which the web of toweling passes to the feed roll supported beneath the tilting container.

This feed roll corresponds substantially to the one shown in Figure 5. The web of clean toweling passes through the gap between the rear wall 28 and the wall of the casing 25 and when a predetermined length of the clean towel has been delivered, the dog will become operative and lock the feed roll against further rotary movement.

I claim as my invention:

- 5 10 1. A towel cabinet comprising a casing having a receptacle for the roll of clean toweling, a feed roll over which the web of toweling passes, said feed roll having a stop thereon, a roll mounted to be engaged by the web of toweling and having a dog thereon to ride on said feed roll and engage said stop, pull of the user on the towel moving said dog to engage said feed roll and release of the towel 15 20 by the user allowing said dog to become disengaged from said feed roll, said dog being arranged between said feed roll and

the roll of clean toweling and actuated positively with each pull of the user on the towel.

25

2. A towel cabinet comprising a casing, a feed roll journaled in said cabinet and having a friction surface over which a web of toweling may pass, a cam fixed to one end of said feed roll and having a shoulder, 30 a guide roll for the toweling web and having said web pass thereunder in frictional engagement therewith whereby movement of the toweling web in delivery tends to rotate the guide roll, and a finger on said guide roll aligned with said cam and having the end engageable by the shoulder of the cam upon the finger being raised by rotation of the guide roll upon delivery movement of the toweling web.

40

In witness whereof, I have hereunto set my hand this 8th day of October, 1921.

GOTTFRID OLSON.
